UNITED STATES PATENT OFFICE.

THOMAS A. LEGGE, OF CHICAGO, ILLINOIS, ASSIGNOR TO THE ADAMS & WESTLAKE COMPANY, A CORPORATION OF ILLINOIS.

DECK-SASH SUPPORT.

Application filed September 6, 1921. Serial No. 498,634.

To all whom it may concern:

Be it known that I, THOMAS A. LEGGE, a citizen of the United States, and resident of Chicago, county of Cook, and State of Illinois, have invented certain new and useful Improvements in Deck-Sash Supports, of which the following is a specification, and which are illustrated in the accompanying drawings, forming a part thereof.

The invention relates to deck sash supports of the ratchet sector type. Its object is to provide means for pivoting the sash such that it may be readily removed, and at the same time to design such means as to firmly hold the sash against lateral movement when in place in the window frame. A further object is to provide a novel form of ratchet sector which will aid in securing the sash against lateral movement, and to provide means for raising and securing the pawl or plunger out of engagement with the ratchet sector when it is desired to remove the sash from the window frame.

In the accompanying drawings:

Fig. 1 is a front view showing a deck sash provided with the improved supports and secured in place in a window frame;

Fig. 2 is a side view of that portion of the supporting mechanism which is secured to the window frame, a part thereof being shown in section;

Fig. 3 is a side view of the complete ratchet mechanism;

Fig. 4 is a side view of the support shown in side view in Fig. 2, portions being shown in section;

Fig. 5 is a front view of the ratchet sector; and

Fig. 6 is a side view of the ratchet sector.

As shown in Fig. 1, a deck sash 10, of usual construction, such as is employed, for example, for ventilating purposes in railway cars or the like, is journaled in the window frame 11, and is normally held in any desired angular position relative thereto by means of a pair of spring-pressed plungers 12, 12, projecting downwardly from housings 13, 13, the base plates of which are secured at opposite ends of the window frame 11.

The plungers frictionally engage the rounded ratchet teeth 14 of the ratchet sectors 15, 15, secured at opposite ends of the sash 10, as by means of screws 16 passing through the base plates 17, 17, of the sectors,

the base plates being preferably cast integral with the ratchet sectors. While two sectors are here shown and described, it is evident that one might be dispensed with and a journal of some other type substituted, 60 the single ratchet serving to hold the deck sash in its adjusted position.

Referring more particularly to Figs. 2 to 6, each ratchet sector 15 is provided with a flange 18 on its outer periphery adjacent the window frame 11. This flange prevents the plunger 12 from slipping out of engaging position with the ratchet teeth due to any looseness in the mounting of the sash. By having a flanged sector on each side of the sash and the plungers 12 bearing on the inner faces of the flanges 18, the sash is positively locked against lateral movement within the window frame.

As a further means of eliminating lateral play of the sash, the trunnions 19, 19, of the sectors 15, 15, are provided with enlarged heads 20, 20, the trunnions being T-shaped in section.

The base plate of each housing 13 extends 80 downwardly therefrom and its lower portion is cut away, as at 21, to form a hook. That portion of each hook which is adjacent the window frame is grooved, as at 23, to accommodate the T-shaped head of the corresponding trunnion. It will thus be seen that the trunnions of the deck sash may be readily fitted in the hooks and the sash thus rigidly held against lateral displacement by means of the closely fitting trunnion heads 20, 20, which are firmly held in the grooves 23.

The housing 13, as shown in Fig. 2, is provided with aligned apertures 24, 25, through which the extremities of the bolt or plunger 12 project. At its forward end the plunger is provided with a bearing collar 26, for one end of a coiled helical spring 22, the other end of which bears against the top wall of the housing 13. The spring thus forcibly holds the bolt in engagement with the ratchet sector.

To facilitate the removal of the sash from the casing there is provided a shaft 29, journaled in the lower ends of the side walls of the casing 13 and offset intermediate of its ends to form a crank 30 for engagement with the collar 26. A crank arm 28 on the shaft 30 serves as means for turning the shaft to lift the plunger out of engagement

with the sector 14. When the handle 28 is in vertical position, as shown in Fig. 3, the crank 30 lies flat beneath the collar. When, however, the handle is swung downwardly 5 the collar is lifted and the plunger raised from the ratchet sector, thus permitting the sash 10 to be removed, its trunnions being readily lifted from the hook 22.

I claim as my invention—

10 1. A pivot mechanism for oscillating sashes comprising an attaching member, a headed trunnion on said member, a second attaching member and a hook-shaped bearing for said trunnion on said last named 15 member, said bearing being provided with a groove for receiving the head of said trunnion whereby said first named attaching member may be detached from said second named attaching member by an upward and 20 lateral movement thereof.

2. In a deck sash support for car windows or the like, in combination, a ratchet sector secured to one side of the sash adjacent the window frame, a trunnion for said 25 sector having an enlarged head, a housing above said sector when the deck sash is in place and secured to the window frame, a bearing for the trunnion also secured to the window frame and grooved to receive the 30 enlarged head of the trunnion, a bolt carried by the said housing and normally projecting therefrom for engaging the ratchet sector, and means for positively raising said bolt and holding the same in elevated position to permit removal of the deck sash.

3. In a deck sash support for car windows or the like, in combination, a ratchet sector secured to one side of the sash, a trunnion for said sector having an enlarged 40 head, a bearing plate for said trunnion secured to the window frame and grooved ad-

jacent the frame to accommodate said enlarged head, a housing secured to the window frame above said ratchet sector when the deck sash is in place, a bolt carried in 45 said housing and its forward end normally projecting downwardly therefrom for engaging the ratchet sector, and a flange on the periphery of said sector between the downwardly projecting bolt and the window frame. 50

4. In a deck sash support for car windows or the like, in combination, a ratchet sector secured to one side of the sash adjacent the window frame, a trunnion for said sector having an enlarged head, a housing above said sector when the deck sash is in place and secured to the window frame, a bearing for the trunnion in the form of a hook also secured to the window frame and 55 grooved adjacent the frame to accommodate the enlarged head of the trunnion, a bolt carried by said housing and normally projecting therefrom for engaging the ratchet sector, a flange on the outer periphery of 60 said sector adjacent the window frame, and positive means for raising and securing said bolt out of contact with the ratchet.

5. In a deck sash support, in combination, a holding catch adapted to be carried by 70 a sash casing, a ratchet sector for attachment to the sash having a latching surface adapted to be engaged by said catch and a radial flange projecting beyond the edge of said latching surface, pivot means for detachably connecting said sash to said casing, said means, catch, sector and flange constituting the sole connection between 75 said sash and casing, and means for raising and securing said catch above said radial flange. 80

THOMAS A. LEGGE.
